Hawley & Hawley

UNITED STATES PATENT OFFICE.

MATHEW HERBERT ALLISON, OF NASHVILLE, TENNESSEE, ASSIGNOR OF
ONE-HALF TO JAMES E. ALLISON, OF SAME PLACE.

PORTABLE FARE-RECEIVER.

SPECIFICATION forming part of Letters Patent No. 451,611, dated May 5, 1891.

Application filed November 18, 1890. Serial No. 371,776. (No model.)

To all whom it may concern:

Be it known that I, MATHEW HERBERT ALLISON, a citizen of the United States, residing at Nashville, Davidson county, State of Tennessee, have invented certain new and useful Improvements in Fare-receivers, of which the following is such a full, clear, and exact description as will enable any one skilled in the art to which it appertains to make and use 5 the same, reference being had to the accompanying drawings, forming part of this specification.

My invention relates to a receiver in which fares or coins may be deposited, and it has 15 reference more especially to fare-receivers used on passenger-cars, and to which access is had to the interior and the contents thereof only by an authorized officer having charge of the key by which the receiver is opened.

20 The invention consists in the various novel and peculiar arrangements and combinations of the several parts of the apparatus, all as hereinafter fully described, and then pointed out in the claims.

25 In the accompanying drawings I have shown my invention as embodied, preferably, in a manually-portable fare-receiver, which is designed and adapted to be carried in the conductor's hand while collecting fares and 30 inspecting and registering the same and to be supported upon a belt worn by the conductor when the receiver is not in use.

In the drawings, in which like numbers of reference designate like parts throughout, 35 Figure 1 is a side view of the receiver supported by the belt of the conductor or person using the receiver, the belt being shown in portion. Fig. 2 is a broad side view of the electric key in circuit with a battery. Fig. 3 40 is a side view of the apparatus shown in Fig. 1 with the electric key applied thereto and about to be forced into electric contact with the contacts of the lock of the receiver. Fig. 45 4 is an enlarged view of the receiver with the fare-pouch removed and the contact-plate of the lock swung to one side. The handle of the receiver is broken away in this view; likewise part of the contact-plate. Fig. 5 is an enlarged sectional view of the receiver 50 with the fare-pouch attached, the plane of the section being indicated by line 55 in Fig.

4. Fig. 6 is an enlarged sectional view of the receiver, the plane of the section being taken through the center of the device at right angles to the section shown in Fig. 5. 55 Fig. 7 is a horizontal sectional view taken on a plane indicated by line 77 in Fig. 6. Fig. 8 is an enlarged view of the fare-receiver, partly in section, of the side of the device opposite to that shown in Fig. 1, the lower 60 part of the pouch being broken away. Fig. 9 is an under side view of the device shown in Fig. 8 with the fare-pouch removed.

Referring to the drawings, 11 designates a shell or casing, made, for instance, of metal, 65 which is curved or rounded at its upper end, and is provided with a removable plate or side 12, which is held in place by means of its upper end taking into a notch 13, formed in a projection upon the upper end of the casing, 70 and the screws 14, which enter perforations in the ears 15, located upon the inside of the casing.

To the lower end of the casing 11 is detachably secured the fare receptacle or pouch 16, 75 which is preferably made of a soft flexible material—such as leather, for instance. The mouth or opening of this pouch is provided with a rigid frame 17, which in the present construction is rectangular in shape in order 80 to conform to the shape of the base of the casing of the receiver over which the frame is designed to fit, as clearly indicated in the drawings. This receptacle or pouch 16 is locked to the receiver by means of an electrically-operated lock, hereinafter to be described, and the coins or fares dropped in the receiver finally reach this pouch, where they 85 lodge until the pouch is unlocked and the contents removed. 90

The coin tube or chute 18, into which the fares are dropped, and through which they finally reach the fare-pouch, is provided with a flaring or funnel-shaped mouth 19, located at the top of the casing, and extends thence 95 down through the casing and to one side thereof to the bottom, where it empties into the fare-pouch. This chute may be formed separately from the casing, and then suitably secured therein, or it may in part be integral 100 with the casing, as desired. The lower part of the coin-chute 18 is provided with a freely-

swinging trap plate or valve 20, which is hinged so that when the receiver is inverted the contents of the fare-pouch 16 will be prevented from passing back through the coin-chute and out of the receiver by the closing of the trap-plate 20 over the chute. This will prevent any one from extracting the contents from the fare-pouch by shaking the same out of the chute.

10 In order that the coin or fares dropped in the coin-chute may be inspected before they are finally deposited in the fare-pouch, I provide an opening or a window 21 at the rear side of the receiver in a convenient place to be observed by the conductor or person collecting the fares. This peep-window is provided with a glass 22, and opens directly into the coin-chute at or near a point where there is located a stop-finger 23, which normally 15 projects into the chute in such a way as to check the passage of any coin or fare deposited in the same and hold it until the finger is withdrawn, which, when the fare-receiver is provided with a register, is operated in conjunction therewith, so that when the stop-finger is withdrawn to permit the deposited fare 20 to escape it and pass into the fare-pouch the register will serve to register the same.

The stop-finger 23 consists in an arm, which 30 is preferably bent, as shown, and projects through an opening 24 in the side of the chute and is mounted upon a rock-shaft 25, so that at each rocking of the shaft the stop-finger may be withdrawn from the passage of the chute and then returned. This rock-shaft 25 is provided with a spring 26, which tends to normally hold the stop-finger within the coin-chute. A trip arm or projection 27 is fixed upon the rock-shaft and is designed to be 35 engaged by a moving part of the register in such manner that at each registration the arm 27 may be tripped, so as to turn the shaft in opposition to the spring acting thereupon in order to withdraw the stop-finger.

40 In the construction shown the register comprises, essentially, a number-wheel 28, provided with a set of numerals 29, and mounted loosely upon a fixed arbor 30, which is secured in a suitable manner within the casing 45 of the receiver. The number-wheel 28 has its periphery formed with teeth 31, which engage the trip-arm 27, thereby causing the stop-finger to be withdrawn and returned as the number-wheel is advanced in its rotation 50 one tooth. A second or totalizing wheel 32 is arranged near the number-wheel. By means of a pin 33 on the number-wheel and gear 34 connected with the totalizing-wheel each revolution of the former will serve to turn the latter one step to record its revolution, as will be readily understood from the drawings. A spring 35 bears upon the gear 34 and acts to prevent an over rotation or a backward rotation of the totalizing-wheel.

55 The lever 36 for operating the register is connected with a sleeve 37, loosely mounted upon the arbor 30, and a spring 38, surround-

ing the sleeve and having one end fixed thereto with the other end secured to an adjacent stationary point, keeps the lever normally 70 pressed upward and serves to return it to its normal position at each operation thereof. The operating-lever 36 projects through an opening 39 in the side of the casing and has its free end provided with a suitable thumb-piece or button. This lever carries a pawl 40, which, by means of a spring 41, connected between the pawl and the lever, is held in engagement with the teeth 31 of the number-wheel 28. The range of movement or sweep 80 of the operating-lever 36 is limited by the upper and lower ends of the opening 39 in the casing, and each depression of the lever will advance the number-wheel forwardly one step, in order to effect the registration of a fare, the pawl 40 moving idly over the teeth 85 in the return movement of the operating-lever.

The register is preferably provided with an alarm consisting in a bell 42, having a hammer or striker 43, which is pivoted at 44 to a bracket 45, which is mounted in fixed position upon the arbor 30. A spring 46, which is connected between the hammer 43 and a rigid arm 47, extending from the bracket 45, 90 tends to keep the hammer pressed toward the bell. A stop 100, mounted upon the bracket 45, limits the movement of the hammer 43 in one direction. Upon one end of the hammer 43 is a fixed pin or projection 48, which is held 95 in engagement with the teeth 31 of the number-wheel. As the number-wheel is turned forward one tooth by means of the operating-lever, the pin 48 is gradually raised to the high part of the tooth, and is then snapped 105 over the point of the same by the force of the spring 46, and this serves in an obvious manner to throw the hammer against the bell and sound the same.

Suitable openings 49 and 50 are formed in 110 the side of the casing, through which the numbers registered by the number-wheel and the totalizing-wheel may be read. However, the register-wheels or the openings are covered by a removable plate or shutter 51, which 115 forms the contact-plate of the electric lock, hereinafter to be described. This plate or shutter 51 is held locked in the position covering the register-wheels, and can only be released so as to expose the register by an 120 authorized person having a key to the lock which holds the shutter. This plate 51 is locked by means of the same lock which secures the fare-pouch.

The electrically-operated lock which secures 125 the fare-pouch or receptacle 16 to the fare-receiver consists in a bolt or latch 52, which engages a shoulder or projection 53, located upon the inner side of the frame 17 of the fare-pouch. The side of the frame 17 opposite 130 that engaged by the bolt 52 is formed with depressions 54, adapted to fit over the heads of the screws 55, which pass through the casing and into the center of the electro-magnets

56 and 57 for holding the same in place. The heads of the screws 55 and the depressions 54, together with the lock at the opposite side of the frame, will serve to securely hold the fare-pouch to the receiver. At the same time it may be easily removed or detached by drawing the bolt 52. The latch 52 projects through an opening 58 in the side of the casing, and is supported upon a frame or yoke 59, which is pivoted at the two points 60 upon the casing. This frame 59 has a slight play on its pivot 60, so that it may be moved toward and away from the casing sufficiently to move the bolt a distance sufficient to lock and unlock it. The bolt 52 is acted upon by a spring 61, which normally keeps the bolt shot or in locked position. Through the center of the spiral spring 61 extends a fixed screw-threaded stem or rod 62, on which works a thumb-nut 63, which is engaged by one end of the spring. By moving the nut one way or the other along the screw-stem the tension of the spring may be varied.

The electro-magnets 56 and 57 are connected by a bridge-piece 64, and the armatures 65 and 66 of the respective magnets are pivoted at the points 67 and 68 to the removable plate or side piece 12 of the casing. The armatures are arranged with their free ends near together, and each one loosely engages the bolt 52, which is formed with a notch 69 at each side thereof for receiving the end of the armature-levers. The frame 59, carrying the bolt, and the armature-levers 65 and 66, which control the same, being mounted upon the plate 12, they are removable with the same. The spring of the lock keeps the bolt normally shot or locked, and the bolt is drawn against the action of its spring, so as to unlock it whenever the magnets are energized and draw down their armatures. The circuit of the lock leads from one of the insulated terminals 70 on the movable plate 12 by the wire 105 over the magnets to the other terminal 70, so that whenever the circuit is completed between the terminals the magnets both act to draw down their armatures, thereby releasing the lock of the fare-pouch. The terminals 70 are engaged by the terminals 71 located upon the inner face of the contact bearing-plate 51, which swings on a pin or screw 72, secured at the upper end of the casing. The wires 105, located between the terminals 70 and the magnets, are sufficiently slack to allow the plate 12, on which the terminals 70 are fixed, to be removed from the casing. This plate 51 is made of suitable insulating material, and is provided on its edges with a metallic wear-plate 73. The outer face of this plate is provided with a great number of metallic contacts 74, which may be arranged in any manner. Some one of these many contacts is electrically connected with one of the terminals 71, while some other one of them is connected with the other terminal 71, while the remaining contacts are not in circuit, but are inert and are sham or decoy contacts, in

order to prevent any one from readily detecting which are the true or active contacts on the lock. When the contact-plate 51 is moved into the position shown, for instance, in Fig. 1, and the fare-pouch is secured to the casing and locked, the latter will serve to hold the plate against movement and to keep it locked until the pouch itself is unlocked and removed.

The contacts 74 of the lock are designed to be engaged by a set of similar contacts 75, carried by the electric key 76. This key in the present construction consists in a thick flat body, made preferably of wood, with one face thereof covered by a sheet 77 of suitable insulating material—such, for instance, as hard rubber. The contacts 75 of the key are set on a flat surface thereof and are designed to be arranged in the same order as the contacts 74 on the lock, with their heads all in the same plane similar to said contacts, so that each contact 75 of the key will engage with one of the contacts 74 of the lock. However, only two of the contacts of the key are in circuit with the battery 78, the wires leading from which are attached to the key by means of the binding-posts 79, which are connected by secret wire with the two active contacts of the key. All the contacts of the key, except those that are active or in circuit, are sham or decoy contacts used to prevent detection of the true contacts, as is the case with the contacts 74 of the lock.

The key 76 is applied to the lock by placing it in the position shown in Fig. 3 and forcing it in the direction of the adjacent arrow into close contact with the contacts 74 of the lock. All of the contacts of the key apparently make contact with those of the lock. The active or true contacts being arranged so as to meet each other, the circuit will be completed from one side of the battery to post 79, one of the active contacts of the key, one of the active contacts of the lock, one of the terminals 71 which is upon the inner side of the plate 51, one of the terminals 70 by way of the electro-magnets to the other terminal 70, thence to the terminal 71 of the plate 51, the other active contact of the lock, the other active contact of the key, the binding-post 79 to the other side of the battery. Whenever this circuit is completed the lock will be released in an evident manner. By this peculiar arrangement of a great number of contacts on the key and the lock, most of which are sham or decoy contacts, it will be practically impossible for any one not having the proper key to succeed in bridging or bringing into circuit the true contacts of the lock.

Various combinations of the true contacts may be made or the combination may be easily changed, so as to increase the difficulty in detecting the proper combination. As the maker of the contact-plate of the lock and also the key need be the only one who knows the combination of the lock, the person au-

thorized to have charge of the key may be kept in ignorance of the combination.

In the drawings I have shown a combination by which the electric combination-lock 5 may be operated. For instance, the contacts 80 and 81 of the lock are electrically connected with the terminals 71 71, respectively, by means of secret connections 82 83, as indicated in dotted lines in Fig. 1. The two contacts 10 84 and 85 of the key, which are each connected with a binding-post 79 by means of the secret connections 86 and 87, indicated in dotted lines in Fig. 2, are arranged so as to make contact with the contacts 80 and 81 of the lock, respectively. The body of the plate 51 is composed of two flat plates 110 and 111, of insulating material, placed flatly together, so that the secret wires 82 and 83 may be conveniently run between the two plates without 20 exposing upon either face of the plate the arrangement of such wires. From this description it will be seen that in order for any one to operate the lock of the fare pouch or receiver he would have to select and electrically connect the two particular contacts 80 and 81. As it would take a number of tedious trials to attempt to discover the combination, and as such attempts would be apt to be observed, no one would be likely to even attempt 25 to tamper with the lock.

There are a variety of ways which will readily suggest themselves in which my peculiar electric combination-lock may be constructed. The construction herewith shown 30 will be found to be a simple and durable one in which the key can be easily handled. In order that the key may be properly guided when applied to the lock, I have provided the same with a guide 88 at the upper portion 35 thereof, which is bent in the shape of the projection at the top of the casing in which the screw 72 is set. The lower part of the key is also provided with a guide 89 at each side thereof, which is slightly resilient in order 40 to clasp the sides of the receiver when the key is forced into position. The guides 89 constitute the ends of a metallic strip, which extends around the back of the key, as indicated in Figs. 2 and 3, and which is secured 45 thereto by suitable screws 90.

The form of the fare-receiver I have herewith shown is a portable one, designed to be carried in the hand by means of the handle 91 when in use in collecting the fares or inspecting and registering them. This handle 50 91 extends vertically downward from a projection or stud 92, which extends from the side of the casing of the receiver at right angles thereto. The handle is arranged so that 55 it may be easily grasped with the fingers and at the same time allow the thumb of the hand holding it to be free to operate the lever 36, which actuates the register and the bell. When the apparatus is not being used to collect fares, it may be hung to a belt 93, carried

60 by the conductor, by means of a hook 94 on the back of the receiver, engaging with a metallic loop 95 on the belt.

The key, which is in the charge of an authorized officer, and which, together with the 65 battery, is to be kept at a station, may be used with a number of different fare-receivers having the same combination, or a different key may be employed with each fare-receiver, the combination of each one of which 70 75 may be different.

There are many modifications which may be made in the construction of my invention without making a departure from the spirit of the same. I therefore desire it to be understood that I do not limit myself to the precise construction herewith shown and described. Of course any character of lock other than the electric one herewith shown 80 85 may be used with my improved fare-receiver.

Having thus described my invention, what I claim, and desire to secure by Letters Patent, is—

1. The combination, with a fare-receiver provided with a register, of a fare receptacle 90 or pouch adapted to be removably attached to the receiver, a lock for holding it thereto and preventing access to the interior thereof, and a plate or shutter controlled by said receptacle or pouch for concealing the register 95 when the receptacle or pouch is locked to the receiver, whereby the register may not be visible or accessible until the receptacle or pouch is unlocked.

2. A fare-receiver provided with a register 100 having an operating-lever, a coin-chute provided with an opening or window for inspection of the coin deposited therein, a movable stop for holding the coin in the chute for inspection, and an alarm-bell, said stop and 105 alarm-bell connected with and controlled by the said registering-lever, whereby as the coin is finally deposited within the receiver the alarm-bell may be sounded and the coin registered.

3. A fare-receiver provided with a register, a movable plate or shutter covering the register-wheels of the register to conceal the same, and a lock for preventing access to the contents of the receiver, said plate or shutter being held immovable by said lock, whereby the register-wheels may not be visible or accessible while said lock is locked.

4. A fare-receiver provided with a register, a fare pouch or receptacle for the receiver, 120 provided with an electrically-operated lock, a movable plate adapted to cover the register-wheels of the register, as a shutter, and provided with contacts in circuit with the electric lock-operating means, the said fare-receptacle engaging the said plate and holding it in the position covering the register-wheels, and a key provided with contacts connected with a source of electricity and adapted to make contact with the contacts of the lock 125 130

for operating the same, whereby the register-wheels may be concealed until the fare-pouch is unlocked.

5. A fare-receiver provided with a register, a fare pouch or receptacle adapted to fit over the end of the receiver and provided with an electrically-operated lock, a pivoted plate provided with contacts in circuit with the electric lock-operating means and adapted to conceal the register-wheels of the register, and an electric key provided with contacts connected with a source of electricity and adapted to make contact with the contacts of the lock to complete the circuit for operating the lock, the free end of said plate being engaged by the said fare pouch or receptacle to hold it against movement when the pouch or receptacle is locked, whereby the register-wheels may not be accessible while the fare pouch or receptacle is locked.

6. The combination, with a fare-receiver having a coin-chute provided with a window for inspection of the coin or fare deposited therein and a positively-operated stop-finger, movable in and out of the path of the coin in the chute for holding the coin or fare at the window for inspection, of a register having a manually-operated lever connected with and controlling the movements of the stop-finger, whereby as the coin is registered the stop-finger is moved to allow the coin to pass and be finally deposited in the receiver.

7. A fare-receiver provided with a register and a lever for operating the register, a coin-chute having a movable stop-finger located therein for checking the passage of the coin for inspection, and a spring-acted rock-shaft carrying the said stop-finger and actuated by the register, whereby the stop-finger and register may be operated together.

8. A fare-receiver provided with a register and a lever for operating the register, a coin-chute having a movable stop-finger projecting therein for checking the passage of the coin for inspection, and a spring-acted rock-shaft carrying the said stop-finger and provided with a trip-arm adapted to be engaged by a moving part of the said register to withdraw the finger and allow the coin to pass as the register is operated.

9. A fare-receiver having a register provided with a register-wheel having a toothed gear moving therewith, a bell having a pivoted spring-acted hammer provided with a projection or pin engaged by the teeth of said gear, whereby the wheel is opposed in its forward rotation by the spring-acted hammer and is locked thereby against backward rotation, and a lever for operating the register-wheel.

10. A fare-receiver having a register provided with a step-by-step-actuated register-wheel mounted loosely on a shaft and formed with a toothed gear, spring-actuated means for opposing the forward rotation of said wheel and then locking it after such rotation, a spring-acted operating-lever mounted upon

said shaft and turning thereon, and a pawl mounted upon said operating-lever and held in constant engagement with the said gear, whereby each vibration of the operating-lever may turn the wheel a step forward.

11. The combination, with a fare-receiver having a casing 11 and provided with a register which may be read through an opening 75 or openings in the casing, of a swinging plate 51, adapted to cover the openings of the casing through which the register may be read, and a lock for holding the plate 51 in closed position, substantially as and for the purpose set forth.

12. The combination, with a fare-receiver having a casing 11 and provided with a register which may be read through openings in the casing, and a swinging plate 51, adapted to 85 cover the openings through which the register may be seen, of a fare receptacle or pouch fitted onto the lower end of the casing and adapted to engage and hold the plate 51 locked in closed position, and a lock for the fare receptacle or pouch, substantially as and for the purpose set forth.

13. The combination, with a fare-receiver having a casing 11 and provided with an electrically-operated lock for preventing access 95 to the contents of the receiver, a register, and a plate 51 for concealing the register when the fare-receiver is locked and provided with a set of suitable contacts 74, one or more of which is in circuit with the electric lock-controlling means, of an electric key 76, provided with a set of contacts 75, one or more of which is in circuit with a source of electricity and adapted to make contact with the contacts 74 of the lock, substantially as and for the purpose set forth.

14. The combination, with a fare-receiver provided with a register having a number-wheel 28, formed with the teeth 31, of a coin-chute provided with a peep-window through which the coin may be inspected before it is finally deposited in the receiver, a stop-finger 23, projecting into the coin-chute to check the passage of the coin for inspection, and a spring-acted rock-shaft 25, connected with the stop-finger and provided with a trip-arm 27, engaged by the teeth of the number-wheel 28, substantially as and for the purpose set forth.

15. The combination, with a fare-receiver provided with a register having a number-wheel 28, formed with peripheral teeth 31, of a spring-acted operating-lever 36, loosely mounted on the shaft with the number-wheel and provided with a pawl 40, having a spring 41 for holding it into engagement with the teeth 31 of the number-wheel, substantially as and for the purpose set forth.

16. The combination, with a fare-receiver having a register provided with a number-wheel 28, formed with peripheral teeth 31, of a bell 42, having a pivoted hammer 43, provided with a trip-pin 48 for engaging the teeth 31 of the number-wheel, and a spring 46 for holding the trip-pin 48 in engagement with

the teeth of the number-wheel, substantially as and for the purpose set forth.

17. The combination, with a fare-receiver having a casing 11, of a fare-pouch 16, provided with a frame 17, a lock having its bolt engaging one side of the frame, projections 55 upon the side of the casing 11 opposite the lock, and the depressions 54, formed in the frame 17 for engaging with the projections 55, substantially as and for the purpose described.

18. A fare-receiver having a register-wheel mounted loosely upon a shaft and provided with a toothed gear, a bell having a spring-actuated hammer engaging the teeth of said gear and operated thereby and acting to lock

the wheel against rotation, and a spring-actuated operating-lever mounted loosely upon said shaft and provided with a pawl held in constant engagement with the said gear, whereby each vibration of the operating-lever 20 may turn the register-wheel a step forward and sound the bell.

In testimony whereof I have hereunto set my hand, this 13th day of November, 1890, in the presence of the two subscribing witnesses. 25

M. HERBERT ALLISON.
